UNITED STATES PATENT OFFICE

VINCENT J. GILMORE, OF WAPPINGERS FALLS, NEW YORK, ASSIGNOR TO THE
DE LAVAL SEPARATOR COMPANY, OF NEW YORK, N. Y., A CORPORATION OF NEW
JERSEY

DESIGN FOR A CENTRIFUGAL SEPARATOR FRAME

Application filed April 18, 1933. Serial No. 47,831. Term of patent 3½ years.

To all whom it may concern:

Be it known that I, VINCENT J. GILMORE, a citizen of the United States, residing in Wappinger Falls, county of Dutchess, State of New York, have invented a new, original, and ornamental Design for a Centrifugal Separator Frame, of which the following is a specification, reference being had to the accompanying drawing, which forms a part thereof.

The figure is a perspective view of a separator frame embodying my design.

The frame tapers from a relatively large diameter top portion downward to an intermediate relatively small diameter portion be-

low the center of the height and thence spreads outward and is split to form four spaced-apart feet, the frame at one side of the intermediate portion being enlarged to form a horizontally extending and approximately cylindrical shaped casing partly intersecting the wall of the frame.

I claim:

The ornamental design for a centrifugal separator frame as shown and described.

In testimony of which invention I have hereunto set my hand at Poughkeepsie, Dutchess County, New York, on this 11th day of April, 1933.

VINCENT J. GILMORE.
